US00D720322S

(12) **United States Design Patent**
Lee et al.

(10) **Patent No.:** US D720,322 S
(45) **Date of Patent:** ** Dec. 30, 2014

(54) **CELLULAR PHONE**

(71) Applicant: **LG Electronics Inc.**, Seoul (KR)

(72) Inventors: **Donghwan Lee**, Gyeonggi-do (KR);
Hongsik Kim, Gyeonggi-do (KR)

(73) Assignee: **LG Electronics Inc.**, Seoul (KR)

(**) Term: **14 Years**

(21) Appl. No.: **29/455,004**

(22) Filed: **May 16, 2013**

(30) **Foreign Application Priority Data**

Nov. 22, 2012 (KR) 30-2012-0055923

(51) **LOC (10) Cl.** 14-03

(52) **U.S. Cl.**

(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the views are included for the purpose of illustrating portions of the cellular phone that form no part of the claimed design.

1 Claim, 6 Drawing Sheets
